ELECTRICAL CONDENSER

Robert C. Sprague, Williamstown, and Frank W. Godsey, Jr., North Adams, Mass., assignors to Sprague Specialties Co., North Adams, Mass., a corporation of Massachusetts

Application May 23, 1940, Serial No. 336,822

11 Claims. (Cl. 175—41.5)

The present invention relates to adjustable condensers and will be described in connection with one of its important applications, which is their use as the variable tuning condensers for the continuous tuning of radio receivers.

The condensers so far used for this purpose are generally and almost exclusively condensers using an air dielectric, and consisting of interleaved rotor and stator plate electrodes. For tuning the respective circuit of the radio receiver, the capacity of the condenser is varied by rotating its rotor plates with respect to its stator plates, thus causing a larger or smaller portion of the two sets of plates to come into close opposition.

As a rule the condensers of the several circuits to be tuned are provided into a single assembly or gang and the capacities thereof are simultaneously varied by a single control, whereby to compensate for capacity differences between the individual condensers of the gang, as a rule one or more so-called trimmer condensers are to be provided.

Notwithstanding their general and almost exclusive use since the advent of radio receivers, such air-dielectric tuning condensers have several shortcomings.

One of these is the large size of these condensers as compared with other types of condensers having similar capacities, because of the low dielectric constant of air and the necessity of a wide spacing between the electrodes of different polarity, due to constructional and operating limitations inherent in such condensers.

A further shortcoming of air tuning condensers is that their plates are subject to nicking or bending and require very careful setting and mounting to keep them in adjustment. Also, to insure mechanical and overall temperature stability, such condenser gangs have to be very substantially built, resulting in an expensive construction.

A particular disadvantage of air tuning condensers is that they are susceptible to "microphonic" action brought about by mechanical vibration of the large and thin electrode plates thereof. Since these vibrations and the microphonics brought about thereby, fall within the audible range reception by the receiver is badly marred.

Altogether, the variable tuning condensers of radio receivers represent one of the few components, which since the advent of radio have undergone no basic change in form; whatever improvements have been made in the design and cost of this component are the result of improve-

ments in manufacturing technique rather than to a change in fundamental design.

While in the past it has been proposed to substitute for air tuning condensers other types of condensers in an attempt to obviate the above drawbacks, the proposed tuning assemblies have not been satisfactory.

10 The reasons for such failure are manifold, but can be generally assigned to unsatisfactory electrical characteristics, lack of mechanical and temperature stability, lack of continuous and sufficiently wide tuning range, complicated construction and high cost.

15 The present invention eliminates the various shortcomings of air tuning condensers without introducing new drawbacks.

Among the various advantages of the condensers of the invention are the following:

20 The condensers are small in size, simple to manufacture, light in weight, and comparatively low in cost, and are mechanically rugged and resistant to wear and atmospheric conditions.

25 The condensers have great mechanical and electrical stability, and such stability is practically unaffected by the humidity and temperature variations which occur under the normal operating conditions of radio receivers.

30 The condensers can be manufactured in mass production within practical capacity tolerances, and with low minimum capacity and wide capacity range.

The condensers are free of microphonic action.

35 In addition, in many cases their use eliminates one or more trimmer condensers which would be required when using conventional tuning condensers and permit exact tracking of the condensers at any position in the tuning range, for example, at the minimum capacity position.

40 In a condenser gang made in accordance with the invention, the individual condensers consist of two coaxial conducting cylinders which form the electrodes, one of which is laterally displaceable with regard to the other, and of an interposed dielectric layer provided on one electrode.

45 More particularly, one of the electrodes is a cylindrical metal core provided with a thin integral dielectric coating of a material of high dielectric constant, and the other electrode is a metal sleeve which slides over the coated core.

50 An important feature of the invention is the close-tolerance sliding fit between the sleeve and the coated electrode, and the extremely small air gap so formed. Special constructional features of the condenser and certain steps in the process 55 of its manufacture insure the reliable operation

of the condenser notwithstanding the small air gap, and also provide for the high stability of the condensers.

For the functional interconnection, into a gang, of the individual condensers, novel constructional means are provided to permit their simultaneous tuning.

It should be well understood that while our invention will be described in connection with variable tuning condensers of the continuous type, it is equally applicable to other types of adjustable condensers, for example, to the condensers used in push button tuning by the so-called "condenser substitution" method.

The various novel features of our condensers and certain steps of making same will now be described in detail in connection with specific examples and with reference to the appended drawings, in which:

Figure 1 is a side view of a condenser assembly in accordance with the invention.

Fig. 2 is a plan view in section along the line 2—2 of Fig. 1.

Fig. 3 is a right side elevation of the assembly of Fig. 1.

Fig. 4 is a sectionized front view of a condenser assembly disclosing another embodiment of the invention.

Fig. 5 is a sectionized side view along the line 5—5 of the condenser assembly of Fig. 4.

Fig. 6 is a side view in section of still a further embodiment of the invention.

Referring to Figs. 1, 2, and 3, the condenser assembly there shown comprises two condenser units 10 and 11 mounted, in a manner later to be described, on a metal base 12, which as a rule is the receiver chassis itself.

Condensers 10 and 11 are of identical construction, except for the differences specifically to be pointed out, and identical parts will be referred to by the same reference numerals.

The condensers 10 and 11 each comprises as one of the electrodes, a metal cylinder 13, and as the second electrode, a hollow metal cylinder or sleeve 14.

Interposed between the electrodes 13 and 14 is a dielectric layer 15, which, according to the invention, is applied as an integral coating to the surface of the inner electrode 13. The dielectric layer 15 is preferably a potassium lead silicate vitreous enamel, as disclosed in the copending application of Stanley O. Dorst, Ser. No. 289,292 filed August 9, 1939, now U. S. Patent No. 2,290,947 issued July 28, 1942, and is cataphoretically applied to the electrode 13.

The dielectric layer may consist of other suitable dielectric materials, for example, of various kinds of porcelain vitreous enamels, or of non-vitreous dielectric materials such as cellulose acetate, "Victron," and hard rubber, to which dielectric materials may be added a filler of titanium dioxide or the like, to increase the dielectric constant and/or lower the power factor. However, irrespective of the particular dielectric used, to obtain the full benefit of the invention, the dielectric layer should be integral with the inner electrode and be applied thereto in a manner as to insure its uniformity in thickness and consistency. So far we have found that such results are best assured by using electro-cataphoretic deposition.

To obtain a high degree of stability, a close tolerance in capacity value, and a reproducible capacity adjustment characteristic, and to make it possible to provide for a large capacity per

square inch of electrode surface, it is essential that the electrodes 13 and 14 possess smooth surfaces, be free of any irregularities, and that the outside diameter of electrode 13 and the inside diameter of electrode 14 be held to close tolerances, for example, within a tolerance range of plus/minus .0001" to .0005". In practice, as a rule, the diameter of electrodes 13 and 14 are held to a tolerance of plus/minus .00025". Such close tolerances can be obtained by the grinding of the outer surface of the electrode 13 and by the reaming or broaching of the inner surface of electrode 14 or by the use of drawn metal tubes for the electrodes 13 and 14.

The dielectric coating is applied to the smoothed outer surface of the electrode 13 preferably by the cataphoretic process described in the copending application of Preston Robinson et al., Ser. No. 197,692, filed March 23, 1938, whereby a thin layer of great uniformity and of even thickness throughout the length of the electrode can be deposited on the electrode 13. As a rule we prefer to also fuse the so deposited coating 15 to the electrode 13, and thereafter subject the coating to surface grinding.

The sleeve electrode 14 engages the coated electrode 13—15 with a sliding fit, whereby an air layer or air gap 16 of very small thickness is formed between the dielectric 15 and the sleeve 14.

A large air gap not only greatly reduces the capacity of the condenser, but we have found, deleteriously affects the stability of the condenser. It is therefore an important feature of our condenser—made possible by its construction and the process steps used in its manufacture—to make the air gap extremely small and of a thickness which is only a fraction of that of the thin dielectric layer 15. We have found that the average thickness of the air layer 16 should be generally less than .0015" and as a rule we provide for a thickness of only .00025 to .0005".

The end portions 17—17 of electrode 13 are tapered. This prevents the coating during its cataphoretic deposition from building up to a greater outside diameter at the edges of the electrode than at the remaining portions. Furthermore, the tapered portions facilitate the sliding of the sleeve electrode 14 over the coated electrode 13—15 and prevent chipping of the coating 15.

To support the condensers 10 and 11 on the base 12, a rigid insulating strip 18 of hard rubber, "Bakelite" or the like, is secured by rivets 27—27 to a metal bracket 26, which in turn is secured by rivets 28—28 to the base 12. According to the invention and for reasons more fully explained hereafter, one condenser is rigidly and the other condenser is flexibly supported on the base 12. It should be noted that the non-microphonic properties of the condenser assembly brought about in a manner later to be more fully described, makes it possible to use the simple mounting method herein described, and eliminates the necessity of providing special damping means such as rubber cushions or the like, as required for conventional tuning condensers.

As shown, the condenser 10 is rigidly supported by means of a threaded spindle bolt 19 which passes through an axial bore 20 of electrode 13, and at one of its projecting ends threadedly engages a threaded metal bushing 34 riveted to the strip 18. Where it enters the bore 20 the bolt 19 is provided with a nut 21.

The condenser 11 is flexibly supported from the

strip 18 by means of a flexible member 22, for example, by a flexible wire of steel or phosphor bronze. At one end, the wire 22 is secured within a hole 37 of the threaded end of a bolt 23, which bolt passes through an axial bore 20 of the electrode 13. At its other end the wire 22 is secured to the strip 18 by being soldered to a metal eyelet 25 which in its turn is riveted to strip 18.

According to the invention, the capacity adjustment of the condensers 10 and 11, which takes place by the lateral movement of the sleeve electrodes 14-14 relative to their respective electrodes 13-13, is simultaneous, this being achieved by the interconnection of the electrodes 14-14 at their top by means of a metal strip 29 (see Figs. 1 and 3), soldered or otherwise secured to them. Strip 29 has two holes 31-31 to which the two ends of a dial cord (not shown) can be attached in known manner. The strip 29 also carries a lug 30 which serves for the outside electrical connection of the sleeve electrodes 14-14.

As an extension of the electrodes 13-13, to guide the electrodes 14-14 in their movement and to support them when moved in the range of minimum capacity setting of the condensers, there are provided guide cylinders 32-32. The cylinders 32 are of insulating material, for example, of hard rubber, "Bakelite," "Isolantite" or the like, and are preferably hollow except for their ends 38 adjacent to the electrode 13. At the ends 38, the cylinders 32 are provided with axial bores 39 through which pass bolts 19 and 23 respectively, which with their heads 40 and 41 secure the cylinders 32-32 to their respective electrodes 13-13.

The cylinders 32-32 have a smaller diameter than have the coated electrodes 13-15, the difference in diameter being of the order of .005" to .01", with a result that the air gap between the sleeve 14 and the guide 32 is correspondingly larger than is the air gap between the sleeve and the coated electrode. This provision is to prevent binding between the guides 32-32 and the sleeves 14-14, which would otherwise occur at certain temperature ranges because of the difference in the temperature coefficients of expansion of the insulating material of the guide 32 and of the metal of the electrode 14. An air gap of the order of .005" to .01" is sufficiently large to prevent such binding, while on the other hand, it is sufficiently small to provide for a positive guiding of the sleeves 14-14 and to insure the exactness of the capacity setting in the range of the minimum capacity setting of the condensers.

Besides being adjustable simultaneously with condenser 11, condenser 10 can also be separately adjusted by the lateral movement of its electrode 13 with respect to its electrode 14. This is achieved by turning the spindle 19 by means of a screw-driver engaging its slotted end 42. This permits the capacity value of the condensers 10 and 11 to be either equalized—preferably at the minimum capacity setting of the condenser—or to assume a constant difference throughout the adjustment range of the condensers.

The capacity setting of condenser 10 so obtained, is maintained by suitable locking means, for example, by a resilient U-shaped metal strip 33 which straddles the strip 18 and is secured to it at one end by means of the bushing 34, and is threadedly engaged at its other end by the spindle 19. The engagement of the strip 33 by the spindle 19 is such that the strip 33 is flexed

5 towards the strip 18 and subjected to a permanent stress. A terminal lug 35 comprising an extending portion of the strip 33 serves as outside electrical connection of electrode 13 of condenser 10, whereas a terminal lug 36 secured by the eyelet 25 serves as outside electrical connection for electrode 13 of condenser 11.

As above pointed out, the support of one condenser is rigid and of the other is flexible. Such an arrangement on one hand, insures maintenance of the relative position of the two condensers throughout their adjustment range, and on the other hand, safeguards against binding between the coated electrodes 13-15 and their respective sleeve electrodes 14.

Furthermore, since each sleeve 14 engages its coated electrode 13-15 with a sliding fit, the sleeve electrodes mutually load and mechanically damp each other, and microphonics due to vibrations or other disturbances are prevented. This damping action of the electrodes is so effective that it eliminates microphonics even with a vertical mounting of the assembly, i. e. with the axis of the electrodes in a vertical position. This damping effect can be further increased by a slight but permanent distortion of the flexible member 22 which supports the coated electrode 13-15 of condenser 11.

As has already been pointed out, an important 30 feature of the condenser of the invention is the small air gap between the sleeve electrode and the coated electrode.

The importance of such a small and uniform air gap will be appreciated if one considers that 35 the air gap forms a series capacity with that of the dielectric coating. As the air has a dielectric constant of only 1, whereas that of the dielectric coating is much greater, for example, the potassium lead silicate above referred to has a dielectric constant of approximately 7, the effective 40 capacity of the condenser is greatly diminished if the air gap is large.

In practice the air gap is made less than one-half of the thickness of the dielectric coating and 45 in general we prefer to keep it between .00025" and .0005".

A close tolerance of the air gap is essential 50 with such a small air gap, not only to prevent binding of the sleeve electrode but also to insure stability of the condenser at all capacity values, and a linear characteristic of capacity change throughout the entire adjustment range of the condenser.

A further important feature of the condensers 55 of the invention is the use of a dielectric which has a high dielectric constant, and which can be applied to the electrode in a very thin layer, and can also be subjected to surface grinding.

A thin dielectric layer is essential for two 60 reasons: First, because the thinner the dielectric the greater the capacity of the condenser for otherwise identical dimensions of its elements. Secondly, the temperature coefficient of the dielectric material being different from that of the 65 electrodes, its different expansion from that of the metal of the electrodes would cause with varying temperature an important change in the thickness of the air layer.

Indeed we prefer to use for the coating a dielectric the expansion coefficient of which closely approximates that of the metal of the electrodes.

The ability of machining, particularly surface-grinding the dielectric, is also of great importance.

The vitreous dielectric material aforesmen-

tioned lends itself excellently to surface grinding, and thus the coating can be ground to very exact tolerances without chipping, and assumes a perfectly smooth surface free of any irregularities as a result of such surface grinding.

The grinding, however, removes the outer glazed surface of the vitreous coating and tends to open pores and fissures exposing the underlying metal of the electrode at such spots. Within such pores and fissures moisture may be absorbed leading to attacks on the underlying exposed metal, which is usually iron, and causing a deterioration of the condenser.

To prevent this, we prefer to subject the coated and surface-ground electrode to the process described in the copending application, Ser. No. 336,821 filed May 23, 1940, of Frank W. Godsey, Jr., which process provides for local corrosion protective platings or coatings wherever the metal is so exposed by the pores.

Another important factor, which makes it possible to reliably operate the condensers of our invention notwithstanding the extremely small air gap existing between the sleeve and the coated electrode, and safeguards the exactness and stability of the capacity settings of the condenser throughout its operating range, is a processing of the condenser elements before and after their assembly into a condenser.

The processing of the sleeve electrode and of the coated electrode before their assembly, consists of the following steps:

For the removal of grease, grit and the like the electrodes are subjected to a caustic wash, for example, in an aqueous solution of 10% sodium hydroxide, this being followed by a rinsing in water.

Thereafter the coated electrode is preferably also subjected to the processing described in the aforementioned application of Frank W. Godsey, Jr., to provide corrosion-resistant local platings or coatings on such portions of the electrode which are exposed by pores or fissures which extend through the dielectric layer.

After this the electrodes are assembled into a condenser and subjected to a special boiling process, which process constitutes an important part of the invention. This boiling in its preferred execution takes place as follows:

The electrodes of the assembled condenser are disengaged and the assembly is placed in a glass container containing vigorously boiling distilled water and left therein for at least one hour. The assembly is then removed from the boiling water and after shaking off the adhering water it is dried preferably by means of an air blast heated to 100° C.

It should be noted that the use of a glass or other non-corrosive container is desirable for when metal containers are used an electrochemical reaction may occur between the metal of the container and the metals of the condenser, which, however slight, may cause metal particles of the container to deposit on the condenser and deterioriously affect its performance.

The effect of the above boiling process is quite remarkable. We have found that condensers which are not so subjected are greatly affected in their stability, particularly with regard to humidity and temperature variations, whereas the condensers which are so processed exhibit a very remarkable degree of stability and their capacity is substantially unaffected by moisture or temperature changes even under very severe operating conditions.

While the effect of this boiling process is not entirely understood, it seems that it removes from the surfaces of the electrodes and of the dielectric coating as well as from the pores of the dielectric coating, all contaminations and all soluble material adsorbed in the dielectric, and the so-boiled surfaces of the condenser element because of their pure and clean condition exhibit a moisture-repelling action.

10 It should be noted that the individual adjustability of the capacity of a condenser of a gang, with regard to the other condensers, eliminates the need of a separate trimmer condenser therefore, to permit exact tracking of the condensers at any position in the tuning range, for example, at the minimum capacity position. This is one of the added advantages of a variable tuning condenser made in accordance with the present invention.

20 While the condensers above described have a straight-line capacity characteristic; i. e. the capacity change is directly proportional to the linear movement of the sleeve, other characteristics can be easily provided by simple and known non-linear mechanical drivers.

25 As illustrative of the compact assembly which the invention provides, and the high capacity range of the condenser units, the dimensions of the elements and electrical characteristics of a typical assembly such as is shown in Figs. 1 to 3 are given.

Length of electrode	
13	inches 1 $\frac{3}{4}$
Diameter of electrode	
35 13	do .5620
Length of sleeve electrode	
30 14	do 1 $\frac{1}{8}$
Inside diameter of sleeve electrode	
40 14	do .5730
Thickness of dielectric layer	
45 15	do .005 to .00525
Maximum variation of outside diameter of layer	
45 15	do plus/minus .0001
Dielectric constant of dielectric material	
50 7	
Average thickness of air gap	
55 16	inch .00025 to .0005
Length of guide cylinders	
50 32	do $\frac{3}{4}$
Outside diameter of cylinders	
55 32	do .565
Power factor at maximum capacity setting	
55 per cent	Approximately or less than .012
Power factor at minimum capacity setting	
60 do	Approximately or less than .05

60 Condensers comprising the above elements have a capacity range of from 6 to 450 μ ufs., and the overall dimensions of an assembly of two of such condenser units such as is shown in Figs. 1 to 3, are only $2\frac{1}{8} \times 1\frac{3}{2} \times \frac{3}{4}$ ".

65 A corresponding tuning condenser consisting of inter-leaved rotor and stator plates occupies approximately five times the volume of the assembly of the invention and furthermore its weight is approximately in the same proportion.

70 It should be well understood that instead of having only two condenser units forming the assembly, as is the case in the foregoing example, the condenser gang may consist, according to the invention, of a larger number of condenser units.

The condensers of the invention also lend themselves for pushbutton tuning or to be used as trimmer or padding condensers, whereby a high stability and wide adjustment range of such condensers is desired.

In Figs. 4 and 5 there is shown a condenser assembly which while also usable as a variable tuning condenser, is particularly adapted for "pushbutton" tuning of a radio receiver; i. e. for the tuning of the resonant circuits of a radio receiver to fixed pre-selected frequencies.

While in practice the number of sets of condensers—which corresponds to the number of frequencies, i. e. to the number of transmitting stations which can be tuned in by the "push-button"—is usually four to ten, and the number of condensers per set—which number corresponds to the number of tuned circuits in the receiver—is usually two to four, for sake of simplicity the assembly shown in these figures consists only of two sets of condensers, and each set consists of only two condenser units.

Neither the circuits of the radio receiver nor the switching means to place the condensers in circuits, need to be described here as such are well known to those skilled in the art.

The assembly will be described with reference to one set only, as the sets are identical in construction.

The assembly of Figs. 4 and 5 comprises an insulating base 50 of hard rubber, "Bakelite" or the like, to which is secured by means of rivets 52—52, a cover 51 open at the two sides. The cover 51 is preferably stamped from a sheet of cold rolled steel or other hard metal.

The condensers are disposed within the cover 51 with their axes perpendicular to the base 50.

Each set comprises two condenser units 53 and 54. These condensers are substantially identical with those described in Figs. 1 to 3 and each comprises a metal cylinder electrode 55, a metal sleeve electrode 56 and a dielectric layer 57 forming an integral coating, preferably of a fused vitreous insulating material, on the electrode 55. It should be here stated that the coated electrodes can be either solid cylinders except for the axial bore, and have been shown as such in Figs. 1 to 3, or may be hollow sleeves or cups and have been shown as such in Figs. 4 and 5.

As shown, the condenser 53 is rigidly supported by means of a threaded spindle bolt 59 which passes through and threadedly engages a threaded axial bore 75 of the closed end of electrode 55, and at its projecting end threadedly engages the base 50.

Condenser 54 is flexibly supported by means of a flexible wire 61, one end of which is secured within a hole 76 of the threaded end of a bolt 63 passing through and threadedly engaging a threaded axial bore 75 of the end of electrode 55. At its other end the wire 61 is secured to the base 50 by being soldered or otherwise fastened to an eyelet 62 which in turn is riveted to the base 50.

The sleeve electrodes 56—56 are secured together by a metal block 72 which conforms to their opposing surfaces and which is soldered to them. A bolt 71 abutting with its head 80 against the top of cover 51 passes through and threadedly engages the block 72 and passes with its free end through a corresponding hole 81 of base 50. The holes in the top of the housing 51 and in the base 50 are sufficiently large to permit free movement therethrough of the bolt 71.

The capacities of condensers 53 and 54 are 75

simultaneously adjusted by vertical displacement of electrodes 56—56 relative to their corresponding electrodes 55—55. This is effected by rotating the bolt head 80.

5 Vertical displacement of the bolt 71 during such rotation is prevented by a collar 73 provided on the bolt and secured thereto at the bottom side of the cover top, for example, by means of a set screw (not shown).

10 For the guiding of electrodes 56—56 in their movement, electrodes 55—55 are each provided with a guide cylinder 65. The cylinders 65—65 are shown identical to the cylinders 32—32 described in connection with Figs. 1 to 3, and are secured to the electrodes 55—55 by means of the spindle bolt 59 and the bolt 63 respectively, similarly as described in connection with the condensers of Figs. 1 to 3.

The adjustment setting of condenser 53 is 20 maintained by a flexed resilient metal strip 68 secured to the base 50 by a rivet 67 and which engages the spindle 59 by means of a tapped hole. An extending portion 66 of strip 68 serves as outside electrical connection for electrode 55 25 of condenser 53, whereas a terminal lug 70 secured by the eyelet 62 serves as outside electrical connection for electrode 55 of condenser 54.

The terminals 66 and 70 of each condenser set 30 electrically connect to a suitable "push-button" selective switching device for connecting the individual condenser sets in circuit in well known manner.

Outside electrical connection to electrodes 56—56 is provided by a lug 74 secured to the base 35 by one of the rivets 52.

In the two embodiments of the invention heretofore described, the condenser units are disposed with their axes in parallel. The invention also lends itself to a tandem arrangement of the 40 units, such an embodiment being shown in Fig. 6.

The assembly shown in Fig. 6 comprises two condenser units 100 and 101 mounted on a common metal base 102 which in practice is preferably the chassis of the radio receiver to which 45 the tuning condenser assembly is applied.

The condensers themselves have essentially the 50 same construction as the condensers of Figs. 1 to 5, each condenser comprising as one electrode a metal cylinder 103 and as the other electrode a metal sleeve 104, the former being provided with a dielectric layer 105 forming an integral coating thereon.

Interposed between the electrodes 104—104 and the base 102 are insulating strips 110—110 of 55 hard rubber, "Bakelite" or the like each having surfaces conforming to the opposing surfaces of electrode 104 and the base 102.

The electrodes 104 are secured to their respective insulating strip 110 by means of a bolt 111 60 whereby the base 102 is cut out at 115 around the head of bolt 111 so as to electrically insulate it from the base 102. Each of the strips 110 is held to the base by a bolt 113.

Outside electrical connection for each electrode 104 is provided by a lug 114 secured to the strip 110 by the bolt 111 and disposed within the cut-out portion 115 of the base 102.

70 Abutting against the left end of electrode 103 of condenser 100 is a guide cylinder 107 of hard rubber, "Bakelite," "Isolantite" or the like, and is preferably hollow except for its end portion 130 adjacent to the electrode 103. Guide 107 and electrode 103 are held together by means of a stud bolt 108 passing through axial bores of electrode 103 and guide portion 130. The bolt

108 is provided at its two ends, where it enters respectively, emerges from the electrode 103 and the guide portion 130, with nuts 109—109.

Abutting against the corresponding end of electrode 103 of condenser 101, is a guide cylinder 116 similarly of hard rubber, "Bakelite" or the like and solid throughout its length except for an axial bore therein. Guide 116 and electrode 103 are held together by means of a stud bolt 117, which passes through axial bores of electrode 103 and guide 116, and is provided at its protruding ends with nuts 118—118.

The electrodes 103—103 are mechanically coupled by means of a flexible element, for example, by means of a flexible wire 119 of steel or phosphor bronze, one end of which is secured within a hole 131 of that end of the stud bolt 108 which extends through the guide portion 130, and the other end of which is secured within a hole 132 of that end of the stud bolt 117 which extends beyond the end of electrode 103 of condenser 101.

External electrical connection for electrodes 103—103 is provided by a flexible conductor 120 secured between the nut 109 and the electrode 103 of condenser 100 and soldered to a lug 121 secured to base 102 by a rivet 122.

Condensers 100 and 101 are simultaneously adjusted by lateral movement of electrodes 103—103 with respect to electrodes 104—104. For this purpose there is secured within a hole 133 of that end of the bolt 108 which extends beyond the electrode 103 of condenser 100, a wire hook element 123, and similarly within a hole 134 of the end of the bolt 117 extending beyond the guide 116, a wire hook element 124.

A dial cord (not shown) is attached in known manner to the hooks 123 and 124.

To limit the lateral movement of electrodes 103—103 beyond that required for minimum and maximum capacity positions of the condensers, a stop 125 is provided on the base 102.

The capacity of condenser 101 can also be adjusted independently of that of condenser 100 by semi-permanent shifting of its electrode 103 with respect to its electrode 104. This is achieved by the simultaneous rotation, in the same direction, of the nuts 118—118 which causes them, together with electrode 103, to move along the bolt 117 either to the left or to the right, as may be required.

While we have described our invention by means of specific examples and in specific embodiments, we do not wish to be limited thereto for obvious modifications will occur to those skilled in the art without departing from the spirit and scope of the invention.

What we claim is:

1. An adjustable condenser assembly comprising two condenser units, each of said units comprising two concentric cylindrical electrodes having cooperating surfaces free of irregularities, and a dielectric layer of uniform thickness and having a ground surface interposed between said electrodes and forming an integral coating on the inner electrode, an air gap .00025" to .0005" in average thickness interposed between the so-coated electrode and the outer electrode, said outer electrodes engaging said coated inner electrodes with a sliding fit, a common mounting member for said inner electrodes, and the outer electrodes mechanically interconnected, means to damp mechanical movement between the outer electrodes and the inner electrodes and to prevent microphonic action in said condenser assembly, said means comprising a resilient mem-

ber securing one of said inner electrodes to the mounting member and biasing the coated inner electrodes against the outer electrodes.

2. An adjustable condenser comprising two concentric cylindrical electrodes having cooperating surfaces free of irregularities, a dielectric layer free of surface irregularities interposed between said electrodes and forming an integral concentric coating on the inner electrode, an air gap of less than .0015" average thickness disposed between said dielectric layer and the outer electrode, and an insulating cylindrical guide member disposed adjacent to and coaxially with said inner electrode, said guide member having an outside diameter less than that of the coating on the inner electrode and said inner electrode comprising a tapered portion adjacent to said guide member.

3. An adjustable condenser assembly, comprising a plurality of condenser units, each of said units comprising two concentric cylindrical electrodes and a dielectric layer disposed between said electrodes and forming an integral concentric coating on the inner electrode, an air gap of less than .0015" average thickness disposed between said dielectric layer and the outer electrode, and mounting means for said condensers comprising a member common to all inner electrodes, a rigid member individual to one of the inner electrodes and a flexible member for each of the remaining inner electrodes.

4. An adjustable condenser assembly, comprising a plurality of condenser units, each of said units comprising two concentric cylindrical electrodes, a dielectric layer interposed between said electrodes and forming an integral concentric coating on the inner electrode, an air gap of less than .0015" average thickness disposed between said dielectric layer and the outer electrode, and mounting means for said condensers, said means comprising a member common to all inner electrodes, a rigid member interposed between said mounting member and one of the inner electrodes, and a flexible member interposed between said mounting member and each of the remainder of the inner electrodes, means to laterally displace the inner electrodes and outer electrodes relative to each other and thereby simultaneously vary the capacity of all of the units, and means comprising said rigid member to independently adjust the capacity of its condenser.

5. An adjustable condenser assembly comprising a plurality of condenser units, each of said units comprising two concentric cylindrical electrodes, said electrodes having cooperating surfaces free of irregularities, an integral fused coating of a vitreous material on the inner electrode forming a concentric dielectric layer thereon and being of uniform thickness and free of surface irregularities, and an air gap of less than .0015" average thickness disposed between said layer and the outer electrode, mounting means for said condensers, said means comprising a member common to all inner electrodes, the inner electrode of one of the condensers being adjustably and rigidly secured to said member, and the remaining inner electrodes being flexibly secured to said member, a common member interconnecting said outer electrodes and means connected to said second member to simultaneously adjust the capacity of the condensers by axial displacement of their outer electrodes relative to the inner electrodes.

6. An adjustable condenser assembly comprising two condenser units, each of said units com-

prising two concentric cylindrical electrodes, a dielectric layer of uniform thickness interposed between said electrodes and forming a concentric coating on the inner electrode, an air gap of less than .0015" average thickness disposed between said dielectric layer and the outer electrode, a rigid member secured to one of the inner electrodes, and a flexible member interposed between said rigid member and the other inner electrode, means to simultaneously displace the inner electrodes relative to the outer electrodes, and means comprising said rigid member to independently adjust the capacity of its condenser.

7. An adjustable condenser assembly comprising two condenser units in tandem arrangement, each of said units comprising two concentric cylindrical electrodes, said electrodes having operating surfaces free of irregularities, a dielectric layer of uniform thickness interposed between said electrodes and forming a concentric coating on the inner electrode, an air gap of less than .0015" average thickness interposed between said layer and the outer electrode, a mounting member common to said outer electrodes, a rigid member comprising a bolt secured to one inner electrode and a flexible member comprising a wire element secured to the second inner electrode and interposed between same and the first inner electrode, means to simultaneously displace the inner electrodes relative to their outer electrodes and means comprising said bolt member to independently adjust the capacity of its condenser.

8. In the manufacture of electrical condensers the process which comprises, disposing on the surface of a cylindrical electrode a concentric coating of a vitreous dielectric material, fusing said coating to said electrode, grinding the surface of said coating to provide same with a surface free of irregularities, assembling the so-

coated electrode into a condenser and subjecting the so-formed condenser to a treatment in hot distilled water.

9. In the manufacture of electrical condensers the process which comprises, disposing on a cylindrical electrode free of surface irregularities, a concentric integral coating of a vitreous dielectric material, fusing said coating to said electrode, grinding the surface of the coating to within a plus/minus .0001" variation in its outside diameter, and thereafter subjecting said coated electrode to a treatment in boiling distilled water.

10. In the manufacture of electrical condensers comprising as elements two electrodes and a dielectric layer interposed between same, the method of stabilizing the condenser against humidity effects which comprises, subjecting said elements to a treatment in hot distilled water.

11. An adjustable condenser assembly comprising two condenser units each of said units comprising two concentric cylindrical electrodes and a dielectric layer interposed between said electrodes and forming an integral coating on the inner electrode, a common insulating mounting member for the inner electrodes, a rigid member interposed between said mounting member and one of said inner electrodes and adapted to laterally displace said inner electrode relative to the surrounding outer electrode and thereby vary the capacity of the condenser, said outer electrodes being rigidly interconnected and being at the same electrical potential and means secured to said outer electrodes to displace the same relative to the inner electrodes and thereby simultaneously vary the capacity of the condenser units.
